UNITED STATES PATENT OFFICE.

GORDON MERRITT, OF RIDGEWOOD, NEW JERSEY.

PIANO-PEDAL.

SPECIFICATION forming part of Letters Patent No. 761,087, dated May 31, 1904.

Application filed May 8, 1903. Serial No. 156,145. (No model.)

To all whom it may concern:

Be it known that I, GORDON MERRITT, a citizen of the United States, residing in Ridgewood, in the county of Bergen and State of New Jersey, have invented certain new and useful Improvements in Piano-Pedals, of which the following is a specification.

This invention relates to the manufacture of that class of pedals which are fitted more particularly for use in pianos and like instruments.

The present improvements provide a sectional construction for a pedal, enabling such article to be made of a plurality of parts, and provides, furthermore, simple means for enabling the parts of the pedal to be rigidly connected one with the other.

In carrying the present improvements into practice the different sections of the pedal may be made in different ways. Thus, for instance, one of the portions—for example, the foot-piece of the pedal—may be cast, while the shank portion may be stamped or bent from sheet metal. I do not, however, wish to limit the scope of the present invention to any particular manner of making the parts of the pedal, as they may all be made by substantially the same method or operation as well as by different.

A further feature of the invention relates to means for supporting the pedal, to thereby enable it to properly function and perform its intended purpose.

The present improvements provide a resilient pedal-support, which not only operates to hold the pedal in proper position for playing, but also returns the same upon the removal of the pressure of the operator's foot.

In the drawings accompanying the present specification I have disclosed an embodiment of my present invention.

In the drawings, Figure 1 is a side elevation, partly in section, of a piano-pedal in whose construction the present improvements are embodied. Fig. 2 is a perspective view of that end of the shank-section of the pedal which is adapted to be engaged with and firmly connected to the foot-piece thereof. Fig. 3 is a corresponding view of the portion of the

foot-piece constructed to engage with the 50 pedal-shank. Fig. 4 is a longitudinal section showing the two sections of the pedal engaged one with the other. Fig. 5 is a perspective view of the spring pedal-support provided by the present invention.

Similar characters of reference designate corresponding parts in all figures.

As already set forth, the present invention provides a construction for making a composite piano-pedal—that is, one built up or made 60 from a plurality of separate sections or parts. In the present instance such sections comprise separate foot and shank sections so formed as to permit the two to be readily connected with each other. The former section is designated 65 in a general way by 2 and the latter by 3. Various means may be employed for connecting the separate sections of the pedal; but preferably some species of interlocking construction is used for the purpose. A convenient and inexpensive pedal construction comprises a shank portion having a bifurcated end, the two projecting members of which bifurcation are somewhat resilient, enabling projecting ears or lugs thereon to be 70 sprung into receiving-sockets in the foot-piece.

In the particular construction illustrated the bifurcated end of the shank portion is so formed as to present a pair of projecting 80 tongues 4 at the sides of the shank, which tongues are substantially parallel, as indicated in Fig. 2, the shank portion being somewhat curved or bent to arc shape in cross-section. Each tongue 4 is provided with a laterally-projecting ear or lug 5, adapted to enter a corresponding receiving-socket in the side of the foot-piece and which may be effected by slightly springing the tongues together and forcing the shank backward into the foot-piece 85 to cause the aforesaid ears 5 to engage with their receiving-sockets 50 therein.

The construction is preferably such that the upper surface of the shank will be substantially flush with the adjacent upper surface of the foot-section, and for this purpose the parts may be so organized that when the aforesaid ears spring into their receiving-sockets the

end of the face 6 will abut against the bottom of the recess between the tongues 4 4. In order to further strengthen the structure, the foot-piece is provided with a projection 7, off- 5 set from the face 6 a sufficient distance to lie on assembling the parts under the upper thickness of the shank portion and carrying at its forward end an ear or lug 8, adapted to engage with a receiving-socket 9 in the shank- 10 section.

The method of assembling the two sections will be apparent from the foregoing description. After the shank has been thrust inward between the side of the foot-piece to cause the 15 lugs 5 5 and 8 to engage as aforesaid these latter may be riveted or headed down to prevent their withdrawal and cause the parts to be firmly held together.

Another feature of the present invention 20 relates to a resilient or spring-like support for a piano-pedal, this support being of such a nature as to perform the dual function of permitting the swinging movement of the pedal as well as effecting the return thereof after 25 the pedal has been pressed down by the foot of the operator and the pressure thereon released. Such support in the form and construction thereof illustrated comprises a spring-strip having a somewhat elongated 30 base 10, provided with openings 11 for securing the support to the floor 12 of the piano. From both ends of this base the spring-strip extends upwardly and inwardly toward each other, (see the portions 13 13,) while the upper ends of these latter are then bent outwardly to form contact portions 14 14, which are designed to be secured directly to the 35 pedal, openings 15 in such portions being provided for the passage of clamping-bolts 16 16. The portions 14 14 are broad enough to span 40 the distance between the opposite edges of the pedal-shank, while at the sides they are provided with inwardly-bent keepers 17 for precluding lateral movement.

45 The bolts 16 16 pass through proper openings in the pedal, a series 18 thereof formed in the upper part of the pedal-shank providing a capacity for the positioning of the spring- support near to or farther away from the foot- 50 piece of the pedal.

55 Constructed in this manner a simple and inexpensive means is provided for manufacturing a composite or sectional pedal and for readily supporting a piano-pedal in such a manner as to enable it to satisfactorily perform its function in the instrument.

Having described my invention, I claim—

60 1. A new article of manufacture, consisting of a piano-pedal comprising a separate foot- piece and shank portion, the latter having a bifurcated end adapted to engage with the foot-piece.

2. A new article of manufacture, consisting of a piano-pedal comprising a foot-piece

formed with receiving-sockets and a separate 65 shank portion having projections adapted to enter between the sides of the foot-piece and ears on said projections adapted to engage with the receiving-sockets in the foot-piece.

3. A new article of manufacture, consisting 70 of a piano-pedal comprising a foot-piece having a forward projection provided with a laterally-projecting lug and which foot-piece is formed with receiving-sockets, and a separate shank portion provided with projections having 75 lugs adapted to engage with the receiving-sockets in the foot-piece and also provided with a receiving-socket for the lug on the forward projection of the foot-piece.

4. A new article of manufacture, consisting 80 of a piano-pedal comprising a foot-piece having a forward depressed projection provided with a laterally-projecting lug and which foot-piece is formed with receiving-sockets, and a shank portion provided with projections having 85 lugs adapted to engage with the receiving-sockets in the foot-piece and also provided with a receiving-socket for the lug on the forward projection of the foot-piece.

5. A new article of manufacture, consisting 90 of a piano-pedal comprising a foot-piece provided with receiving-sockets in opposite sides and a forward depressed projection having a laterally-extending lug at its forward end, and a separate shank portion provided with a series 95 of cut-away portions disposed longitudinally thereof and which shank is formed with projections having laterally-extending lugs adapted to engage with the receiving-sockets in the foot-piece, the shank portion having 100 also a receiving-socket for the lug on the forward projection of the foot-piece.

6. A new article of manufacture, consisting of a piano-pedal combined with a spring-support 105 formed from a strip of spring metal having reversely-bent ends, the extremities of which are secured to the shank of the pedal.

7. A new article of manufacture consisting of a piano-pedal comprising a shank portion 110 formed with cut-away portions disposed longitudinally of the shank, in combination with a spring-support comprising a bent strip of spring metal, and clamping-bolts for securing said support to the pedal whereby the positioning of the clamped support along the pedal 115 may be effected at different points.

8. A new article of manufacture consisting of a sectional piano-pedal, the shank portion of which is secured to the foot portion and is formed with cut-away portions disposed longitudinally of the shank, in combination with a spring-support comprising a bent strip of spring metal, and clamping-bolts for securing said support to the pedal whereby the positioning of the clamped support along the pedal 120 may be effected at different points.

9. A new article of manufacture consisting of a sectional piano-pedal comprising a shank

portion and a foot portion secured thereto and which shank portion has a series of perforations in its upper part, combined with a resilient support formed from a bent strip of metal, and clamping-bolts adapted to pass through the perforations in the shank portion of the pedal whereby the positioning of the

clamped support along the pedal may be effected at different points.
